SCISSORS OR THE LIKE

Ernest Hardin, Ardmore, Okla.

Application August 12, 1940, Serial No. 352,300

1 Claim. (Cl. 30—254)

My invention relates to improvements in scissors, shears, or the like, whereby the manual operation of scissoring or shearing is rendered more efficient and easy, and accurate, with considerably less effort than is required for the same operations in using conventional shears.

Important objects and advantages of my invention will be apparent from a reading of the following description and the appended drawing, wherein are shown preferred embodiments of my invention for illustrative purposes.

In the drawing:

Figure 1 is a general side elevational view of a scissors or shears in accordance with the present invention.

Figure 2 is an opposite side elevational view of a slightly modified form.

Referring in detail to the drawing and first to the embodiment shown in Figure 1, which is generally designated by the numeral 5, the numeral 6 designates the usual screw pivot which connects the scissors or shear blades 7 and 8 in overlapping relation, the blades having handles 8' and 9, respectively, extending on the opposite side of the pivot. In ordinary scissors or shears the cutting edges 10 and 11 of the respective blades are substantially straight, whereas in the present invention these edges are divergently curved at an angle of divergence ranging from one degree to 35 degrees and as high as 40 degrees, and the handles 8' and 9 are similarly divergently curved at a similar angulation to that provided for the cutting edges 10 and 11. In addition, the shoulders 12 and 13 at the junction of the handles with the blades at the handle side of the pivot 6 are cut away at a sufficiently sharp angle and to a sufficient extent to permit the full closing or occlusion of the terminal portions of the cutting edges 10 and 11 by closing the handles 8' and 9.

By reason of the arrangements described the cutting action can begin at the very inner terminals of the cutting edges 10 and 11 where the leverage factor of the handles 8' and 9 is greatest. Further, the cutting action acts with substantially increased power over ordinary shears or scissors right along the cutting edges 10 and 11 as far as the terminals 14 and 15 of these cutting edges as the handles are brought together, correct angulation of the cutting edges

obtaining for most efficient cutting and easy operation throughout the entire length of the cutting edges as the handles are brought together.

5 In the modified form shown in Figure 2 of the drawing both of the handles 8a and 9' are not completely divergently offset as in the case of the above described embodiment, but the handle 9' is curvedly displaced somewhat toward the handle 8a, while the cutting edge 10a of the blade 7a corresponding to the handle 9' has the same divergent curvature with respect to the cutting edge 11a of the blade 8a. Further, the arrangement of shoulders such as the shoulders 12 and 13 is eliminated by having the blades 8a and 7a strictly in side by side arrangement, with the terminals 15a and 14a both pointed or leaf-shaped instead of having the terminal 14 of the first described embodiment angularly truncated as indicated by the numeral 14'. The arrangement of the second described embodiment provides in a slightly modified type of shears, the essential features of operation and efficient mechanical advantage provided for in the first described embodiment.

Although I have shown and described herein preferred embodiments of my invention, it is to be definitely understood that I do not desire to limit the application of the invention thereto except as may be required by the scope of the subjoined claim.

Having described the invention, what is claimed as new is:

35 Shears or the like constructed with a departure from the normal by having the blades thereof curved longitudinally for the full length of the blades; said blades being curved away from each other in opposite directions from the pivotal point of the blades toward the terminals 40 of the blades whereby, upon closing of the blades in initiating a cutting action such cutting action will begin immediately at the point of the pivotal connection of the blades so that the cutting edges of the blades for the full length 45 thereof are availed of in effecting the cutting operation, the handles of the shears having divergence with respect to each other similar to the divergence of the blades.
